United States Patent Office.

HENRY NUSTEDT, OF NEW YORK, N. Y.

Letters Patent No. 96,830, dated November 16, 1869.

IMPROVEMENT IN SAMPLE-CARDS FOR LIQUIDS.

The Schedule referred to in these Letters Patent and making part of the same.

To all to whom it may concern:

Be it known that I, HENRY NUSTEDT, of the city of New York, county and State of New York, have invented certain Improvements in Sample-Cards for Liquids; and I do hereby declare that the following is a full and exact description thereof, reference being had to the accompanying drawing, and to the letters of reference marked thereon.

The nature of my invention consists in constructing a sample-card with no sides to it, so that by holding the whole card up to the light, you can select the color; and, the glasses being of the same diameter, the degree of fluidity of the different liquids can be readily detected; further, in holding all the tubes in their places, by a slide passing over the top of the tubes.

To enable others skilled in the art to make and use my invention, I will proceed to describe its construction and operation.

Figure 1 is a side elevation of my sample-card, when closed, to be carried in the pocket.

Figure 2 is an end elevation, when in the above state.

Figure 3 is an elevation of the same, when open and ready for inspection; the right half is in elevation, the left half a central vertical section.

Figure 4 is a cross-section on line T T, fig. 3.

Figure 5 is a plan view, the slide partly removed.

A is the wooden frame.

It consists of two side strips, *a a'*, the bottom strip *b*, and the top strip *c*.

The top strip *c* has a number of holes drilled through, through which are passed the glasses B B B, which are to contain the liquids.

The lower strip *b* has, just opposite to the holes in *c*, drilled holes of the same size, but not entirely through the strip.

The lower part of B is inserted in these countersinks in *b*.

The upper strip is hollowed out at the top, at *d*, to give room for the corks on the glasses B B.

All the glasses are held in their position by a slide on the upper strip, denoted in the drawing by C.

This slides in notches *e e*.

The corks are cut in such a manner that the slide passes closely over them.

By these means the glasses are prevented from lifting out from the lower holes, in bottom strip *b*, and are held securely in their desired position, whatever position the card may be placed in.

The glasses being held in this manner in a frame, consisting of a top, bottom, and side pieces, it is readily understood, there being no ends, that, by holding the glasses up to the light, their contents may be scrutinized closely, and much easier a comparison between all of the liquids is formed, having them all before your eyes at once, than by the old sample-card, where you have to take them one by one from a closed case.

For safety, in carrying this sample-card, I surround the same by folding sides, similar to a pocket-book.

D is the short flap,

E, the long flap, coming over the top of the card, and folding over D.

The flaps are secured by catch and lock F.

On flap D is pasted a strip of paper, on which may be marked the name and price of the different articles just opposite the glasses which contain the same.

Having now fully described my invention,

What I claim as new therein, and desire to secure by Letters Patent, is—

Frame A, consisting of bottom, top, and side strips, in combination with glasses B B and slide C, substantially as specified.

HENRY NUSTEDT.
